PORTABLE BLOWER

Julius W. Rubin, 94 Reed Drive, Roslyn,
Long Island, N.Y.

Filed Oct. 23, 1965, Ser. No. 87,863

Term of patent 7 years

(Cl. D62—2)

I claim:

The ornamental design for a portable blower, substantially as shown.
